US00D592064S

(12) **United States Design Patent**
Kilany

(10) **Patent No.:** **US D592,064 S**
(45) **Date of Patent:** **** May 12, 2009**

(54) **PACKAGING**

(75) Inventor: **Hiba Kilany**, Beirut (LB)

(73) Assignee: **Cadbury Holdings Limited**, Uxbridge (GB)

(**) Term: **14 Years**

(21) Appl. No.: **29/285,364**

(22) Filed: **Mar. 28, 2007**

(30) **Foreign Application Priority Data**

Sep. 29, 2006 (EM) 000597950

(51) **LOC (9) Cl.** **09-01**

(52) **U.S. Cl.** **D9/519; D9/551**

(58) **Field of Classification Search** D9/500, D9/502-505, 16, 519, 521, 529, 545, 549, D9/551, 558, 424, 426, 428, 435, 715; D7/510, D7/523, 538; D28/91.1; 215/381-385, 396, 215/398; 222/548; D24/104

See application file for complete search history.

(57) **CLAIM**

The ornamental design for a packaging, as shown and described.

DESCRIPTION

FIG. 1 is a top perspective view of my ornamental design for a packaging of the present invention;

FIG. 2 is a top plan view of the packaging of FIG. 1;

FIG. 3 is a bottom plan view of the packaging of FIG. 1; and, FIG. 4 is a top perspective view showing of the packaging of FIG. 1 with the lid laid under the container in an open condition.

The broken lines shown in the drawing views are included for the purpose of showing environmental structure that forms no part of the claimed design.

1 Claim, 3 Drawing Sheets
